UNITED STATES PATENT OFFICE.

DAVID D. JONES, OF OAKLAND, CALIFORNIA.

CLOTHES HANGER.

Application filed January 19, 1927. Serial No. 162,019.

My invention relates to the class of hangers especially adapted for suspending clothes, particularly for drying them. Although the device may be used in any suitable location 5 outside of or within doors, it is designed more particularly for setting up in a room, for example, a kitchen; and for this purpose its structure is such that it may be readily assembled to upright position on a stable 10 base, and its hanging-line unit vertically adjusted within reach of the user and then lifted to the ceiling to be fully out of the way.

This type of clothes hanger is exemplified 15 by my former Letters Patent No. 1,037,487 dated September 3rd, 1912; and as my present invention is an improvement upon the device therein disclosed, said patent may be referred to in the present connection.

20 Any device of this nature must be capable of ready dismemberment and reassembling, not only to set it up in and remove it from its position of use, but also to enable it to be reduced to and packed in sufficiently small 25 compass for economical shipping, particularly by parcel-post. The first object of my present invention concerns this matter of shipping convenience, and is attained by a novel construction of the hanging-line unit 30 whereby its separated side bars when removed from the supporting cross bar may be brought close together and the numerous and relatively long line-wires connecting the side bars may fold and bend neatly and without 35 kinking or entangling. The hanging-line unit may thus be reduced to relatively small compass for shipment without such distortion as would tend to defeat expansion of the unit to perfect shape.

40 Another object of my invention is to so arrange the association of the hanging-line unit and its supporting cross bar, with the hoisting mechanism, as to automatically compensate for any lengthening of the hoisting 45 lines, so that said unit is kept level; and this novel association has a further object of providing a simple and effective releasable joint, insuring the lateral stability of the hanging-line unit.

50 Another object of my invention is to im-

prove the sectional structure of the supporting cross bar whereby it is rendered more rigid as a whole, and is adapted to be taken apart for packing.

Other objects of my invention will appear 55 in the course of the following description, read in connection with the accompanying drawing, wherein is illustrated the preferred form of my clothes-hanger, though it is to be understood that changes may be 60 made without departing from the spirit of the invention as defined by and within the scope of the claims hereunto appended.

In the drawings—

Fig. 1 is a perspective view of my clothes 65 hanger set up in a room, the hanging-line unit being elevated part way.

Fig. 2 is a side view of one end of the device showing the arrangement of the hoisting 70 lines.

Fig. 3 is a view of the same at right angles to Fig. 2.

Fig. 4 is a top view showing the connection of the supporting bar with the follower block.

Fig. 5 is a side elevation, partly in section, of Fig. 4.

Fig. 6 is a section, enlarged, on the line 6—6 of Fig. 4, showing the novel pivotal connection of the hanging wires with the 80 side bars.

Fig. 7 is a side elevation broken, showing the sectional structure of the supporting cross bar.

Fig. 8 is a section on the line 8—8 of Fig. 85 7, the bolt being omitted.

Fig. 9 is a perspective view of the hanging-line unit when folded for shipment.

In Fig. 1 the numerals 1, 1 are the posts of the structure set up in a room. To insure 90 their stability, they may have foot brackets 2 or they may be otherwise braced or secured or clamped to the floor 3 or the wall of the room.

4 is the supporting cross bar upon which 95 are adjustably slidably fitted the side bars 5 which with the wires 6 comprise the hanging-line unit of the device. The cross bar 4 is made in sections, three sections being shown in Figs. 1 and 7, one riding on the 100

other two and relatively slidably by means of a tongue 4' in the former and grooves 4" in the latter—see Figs. 7 and 8. The bar 4 may thus be lengthened or shortened and held by bolts 4^a and nuts 4^b and may be disjoined for packing.

When assembled, the sections of the bar 4 are quite rigid and free from relative rocking movement.

10 The side bars 5 of the hanging-line unit are adjustably fitted to the end sections of the bar 4, by means of bolts 5', passing through the grooves 4" and nuts 5" on said bolts, as seen in Figs. 4 and 5.

15 The wires 6 of the hanging-line unit have their ends fastened to the bars 5 in such wise that there is relative rotary play in the connection. This pivoting may be effected in any suitable manner, but the simplest and 20 preferred way is that shown, in Fig. 6, namely, the wire being bent at 6' and passed freely through the bar, and its projecting end 6" then forwardly bent in the same direction as that in which said wire approaches the bar. This forward bending of the protruding wire end is essential to the security of the wire, for if not so bent, or if bent in a return direction it will pull out under the weight of the clothes. But with 25 the forward or outward bend as shown in Fig. 6, the wire will not pull out, and though other expedients, to prevent pulling out, such as heading up or enlarging the wire ends might be resorted to, the bend shown 30 is the simplest and most effective form of the pivotal connection.

This pivotal connection between the side bars and the wires is in contradistinction to and decided contrast with former practise, 40 such for example as weaving a continuous wire back and forth, or of wrapping the wire ends around the bars. With such former connections it would manifestly be inadvisable to attempt the folding of the 45 hanging-wire unit by bringing its side bars close together to pack it for shipment. To do so would kink the wires badly right near the bars, and tangle up their middle portions in such confusion that it would be 50 difficult to straighten them out. But with the pivotal connection herein described, the side bars 5 may be brought close together, and in so doing the wire ends will turn in the bars, and not kink, so that as shown in 55 Fig. 9, a neat bundle in relatively small compass adapted for convenient shipment, even by parcel post, may be made of the unit, the wires lying neatly side by side and their middle portions suffering only a bend of 60 relatively long and consequently safe radius, easily returned to shape.

When the package is thus folded for shipment, temporary ties, such as indicated at 7 and 8 in Fig. 9 will be used.

65 Assembled with one of the posts 1 and

parallel therewith, as seen in Fig. 1, is a guide rod 9, upon which is slidably mounted, as indicated by the eye 10' in Figs. 4 and 5, a follower block 10.

The hoisting tackle by which the supporting cross bar 4 and hanging-line unit 5, 6, are raised and lowered is not essentially different from that disclosed in my previous patent hereinbefore referred to. Such tackle, as shown in Figs. 1, 2 and 3 comprises the first rope 11, one end of which is secured at 11' to the follower block 10. Said rope thence passes to and around a pulley 12 in a bracket 13 carried by the upper end of the post 1 and down to a pulley 14 in the follower block; thence up to second pulley 15 in the bracket 13 and down to a cleat 16 on the post. A second rope 17 is secured at one end 17' to the upper end of the opposite post 1, as seen in Fig. 1, and thence passes down around a pulley 18 in the end of the supporting cross bar 4; thence across and parallel with said bar to a pulley 19 in the block 10 and thence to a fastening 20 on the post 1. By this arrangement the hanging-line unit rises and lowers perfectly horizontal.

The connection between the follower block 10 and the end of the supporting cross bar 4 must be one which will insure the lateral stability of the bar and its hanging-line unit, so that they will not tip, this being essential since the other ends of these members are carried only by the second hoisting rope 17. Such stable connection I have 100 provided by means of a novel joint in which is included the further object of keeping the hanging-line unit level endwise by automatically compensating for any variation in the length of the hoisting ropes. The joint 105 as shown in Figs. 4 and 5 comprises a slotted plate 21 secured to and projecting from the follower block 10 and the slotted end 4^c of the supporting cross bar 4 which fits over said plate, said end having a cross pin 22 entering and pivotally playing in the slot of the plate 21. Thus the connection is one which is easily made and broken, and at the same time is a laterally stable one, and an endwise pivotal one for the hanging-line 115 unit.

I claim:—

1. A clothes hanger comprising a pair of posts; a supporting cross bar carried by and vertically adjustable between said posts; parallel spaced side bars rectangular in cross section fitted upon said cross bar; wires extending between said side bars and having their ends bent and pivotally fitted through the bars from one horizontal surface to the other and thence bent again in the same direction as the approach of said wires to the bars.

2. A clothes hanger comprising a pair of posts; a supporting cross bar between said

posts, said bar having a slotted end; side bars fitted upon said cross bar at opposite ends; wires extending between said side bars; a vertically slideable follower block carried by one of said posts; hoisting lines for suspending said cross bar from the posts; a slotted plate carried by the fol-

lower block over which the slotted end of said cross bar is fitted; and a cross pin carried by the slotted end of the bar and seated in the slot of said plate. 10

In testimony whereof I have signed my name to this specification.

DAVID D. JONES.
